THRESHOLD WEATHER STRIP.

Filed July 31, 1929

UNITED STATES PATENT OFFICE

WILLIAM B. BAILEY, OF OLYMPIA, WASHINGTON

THRESHOLD WEATHERSTRIP

Application filed July 31, 1929. Serial No. 382,412.

I am aware that various types of threshold weatherstrips have been used at the bottom of doors held in closed position by springs, etc., but I am not aware that it is old to place 5 a weatherstrip in a vertical groove in the bottom edge of a door and secure the strip in such groove so that it is free to move vertically therein and provide means for holding the strip in the groove when the door is open 10 so that when the door is open the end of the strip beyond its support and toward the free side of the door may drop by gravity below the plane of the threshold, whereby the point of contact between the threshold and strip 15 at the beginning of the closing of the door is of comparatively small area, which area increases until the door is fully closed, whereby the strip is the more easily moved to operative position without undue friction, and 20 when the door is fully closed the strip by gravity moves to sealing relation to the threshold.

In the drawings:

Figure 1 is a front elevation of a door embodying my invention.

Figure 2 is a detail front elevation showing the door partially open.

Figure 3 is a transverse sectional view through the bottom of the door and the door 30 frame, the door being shown open in dotted lines.

Figure 4 is a vertical sectional view through the bottom of the door showing the slot and the strip mounted therein.

Figure 5 is a perspective view of the strip.

The reference numeral 1 designates a door frame having a threshold 2, said frame having a hinged door 3.

The bottom edge of the door is provided 40 with an elongated groove 4 extending the full width of the door and of equal depth and width throughout its length. A weather or sealing strip 5 is mounted in said groove 4 and is of such dimensions that while it will freely move vertically in said groove it will not bind therein. This strip is provided with an elongated slot 6 which extends substantially 45 above the longitudinal axis of the strip and is positioned between the center of the strip and that end of the strip located at the hinge 50

side of the door, whereby one end of the strip is heavier than the other when the strip is suspended in the groove 4 on the pin 7. The pin 6 is secured near the bottom of the door and passes transversely through the groove 55 4 of the door and slot 6 of the strip 5.

The pin 7 functions as a fulcrum and as a guide for the weatherstrip 5, and the location of the pin between the center and hinge side of the door is such as to cause the inner or 60 hinge end of the strip to move upward in the groove 4, and the outer end of the strip to move downward in the groove when the door is opened and swung clear of the threshold. This tilting of the strip results in reducing 65 the area of contact between the strip and threshold when the door is moved to closed position thereby reducing friction and gradually moving the strip upward into operative 70 position in the groove 4, and when the door is fully closed the strip by gravity moves to sealing relation with the threshold.

In some instances the dropping of the weatherstrip 5 by gravity when the door is opened might produce a noise incident to the 75 end of the strip at the hinged side of the door striking the top of the groove 4, and in order to overcome this I insert a comparatively short piece of rubber 8 at the top of the groove at the hinge side of the door. 80

What I claim is:

The combination with a door having an elongated groove in its bottom edge, a pin extending transversely through said groove and positioned substantially midway between 85 the hinged side of the door and the middle thereof, an elongated weatherstrip bodily movably mounted in said groove and free to move bodily downward by gravity and provided with an elongated slot extending vertically above the longitudinal axis of the strip, and adapted to receive said pin, whereby the strip is free to move vertically in said groove and adapt itself to the threshold of the door to form a tight joint therewith, and a cushion 90 in the top of the groove at the hinge side of the door. 95

In testimony whereof I affix my signature.

WILLIAM B. BAILEY. 100
